UNITED STATES PATENT OFFICE.

WALTER E. E. MILZ, OF NEW YORK, N. Y., ASSIGNOR TO PHINNEY-WALKER KEYLESS CLOCK COMPANY, OF NEW YORK, N. Y., A CORPORATION OF MASSACHUSETTS.

STOP MECHANISM.

1,031,806.

Specification of Letters Patent.

Patented July 9, 1912.

Application filed October 7, 1911. Serial No. 653,378.

To all whom it may concern:

Be it known that I, WALTER E. E. MILZ, a subject of the Emperor of Germany, residing at New York city, in the county of New York and State of New York, have invented certain new and useful Improvements in Stop Mechanism, of which the following is a specification.

This invention relates to stop mechanisms for time pieces, and especially adapted and intended for use in connection with clocks in which the spring may be wound or the hands may be set by rotation of a casing which surrounds the movement, the casing being pulled in or out to respectively engage spring winding gearing, and hand setting gearing. Clocks of this type have heretofore been disclosed in my Patent No. 1009773 and pending applications Nos. 638,343 and 20 643,311.

The present invention is illustrated as applied particularly to the clock shown in the last mentioned application, No. 643,311, in which the hand setting gearing incloses an arbor at the central axis of the movement, on which is a clutch which is operated by shifting the casing when the hands are to be set.

It is desirable for various reasons to provide such clocks with a stop seconds hand, and it is the object of the present invention to do this. It is to be understood, however, that the invention may be applied to clocks having a different construction to that disclosed in the applications above referred to, and no limitation in this respect is implied.

The invention is illustrated in the accompanying drawings in which—

Figure 1 is a plan view illustrating the stop mechanism in engagement, the dial plate and parts above the same being removed. Fig. 2 is a similar view with the stop mechanism disengaged. Fig. 3 is a central longitudinal section of the clock. Fig. 4 is a side elevation of a part of the movement. Fig. 5 is a detail showing the push button for actuating the stop device. Fig. 6 is a detail in section showing a spring to support the bezel which holds the 50 glass.

Referring specifically to the drawings, 15 indicates an arbor at the central axis of the movement, which is driven from the spring barrel 16 by a train including a gear 17 on the barrel, a pinion 18 and gear 19 on an in-

termediate arbor 20, a pinion 21 and gear wheel 22 on the arbor 15. The pinion 18 and gear 19 are only friction tight on the arbor 20, and the pinion 21 and gear 22 are only friction tight on the arbor 15. In my 60 application No. 643,311, above referred to, the arbor 15 extends through the dial plate and carries the hands, in a known manner, but in the present invention this construction is modified, and instead of extending 65 through the top plate 23 of the movement, the arbor 15 has a bearing therein, at the top, as indicated at 16', and the power of the spring is communicated to the hands from the arbor 20 of the movement, which 70 above the top plate carries a gear 24 which meshes with a pinion 25 on the quill 26 which carries the minute hand 27, and said arbor 20 also carries a gear 28 which meshes with a gear 29 on the quill 30 which carries the 75 hour hand 31. The hands, therefore, instead of being carried by the central arbor as usual, are driven by motion transmitted through the gearing above described from the arbor 20. The wheel 22 is connected 80 to the escapement by a suitable and known train, which need not be described here, but which includes an arbor 32 which turns once a minute, as usual, and which extends 85 through the front plate 23 of the movement and drives the stop hand in a manner to be presently described.

As disclosed in my application above referred to, when the inner casing 7 is pulled out the arbor 15 is engaged to set the hands 90 by turning the inner casing, and for this purpose it is provided with a gear wheel 33 fast thereon and meshing with a wheel 34 which is fast on the arbor 20, and during this action the friction tight gears 18 and 19 95 and 21 and 22 slip on their respective arbors. When the hand setting devices are disengaged, the wheels 33 and 34 turn idly with the arbors.

Mounted upon the front plate 23 is a 100 bridge 35 which forms a support for the quills 26 and 30 and which is also provided with a tubular bearing 36. The staff or arbor 37 which carries the seconds or stop hand 38 extends through this tube, at the 105 central axis of the clock, and has a bearing at 38a on the front plate 23. Under the bridge, the arbor 37 has thereon a gear wheel 39, which is capable of being engaged by a gear wheel 40 carried by a lever 110

41 which is pivoted at 42 to the top plate, and the gear wheel 40 is in mesh at all times with a gear wheel 43 at the upper end of the arbor 32 which, as stated, forms 5 a part of the escapement train and which turns once a minute. When the gears 39 and 40 are engaged the seconds hand 38 is driven, and when disengaged, it is stopped. A spring 44 tends to throw the 10 lever 41 to engage said gears. 45 indicates a cam wheel which has notches 46 into which the bevel point 47 of the lever 41 will drop when it registers with said notches. Rigid with the cam wheel 45 is 15 a gear 47', and these parts turn on a stud 48 on the front plate. The wheel 47' meshes at a right angle with another wheel 49, the arbor 50 of which is carried by a block or bracket 51 on the underside of the front 20 plate, and said arbor 50 also carries a ratchet wheel 52 engaged by a spring pawl 53 at the lower end of a push pin 54 which works through a hole in the dial plate 55 and projects above the dial to contact with 25 a projection 56 on the inner side of a bezel 57 which holds the glass 58. At a diametrically opposite point the bezel 57 is hinged at 59 to the dial plate. To cause the stop hand 38 to fly back after each 30 operation a lever 60 is provided, and one end is pointed as at 61 to drop into one of the notches 46 by the force of a spring 62. The other end of the lever 60 which lever is pivoted at 63, is arranged to strike 35 a heart cam 64 on the arbor 37 of the seconds hand, and this action takes place when the point 61 of the lever 60 rides up onto one of the rises of the cam wheel 45, as shown in Fig. 2. This return action 40 is common in stopping movements. The inner casing 7 carries a rim 8, as disclosed in my said application, by means of which the casing may be pulled out or pushed in, and turned, to set the hands or wind the 45 spring. The rim 8 laps the bezel 57, as indicated at 8^a, and a packing ring 8^b is inserted between the rim and the bezel, to prevent the entrance of dust.

The stop hand may be driven by other 50 devices if desired, the invention relating especially to the means for operating the stop mechanism.

In the operation of the parts above described, when pressure is applied to the 55 face of the glass 58, and it is pushed in, it forces in the pin 54, which turns the ratchet 52 one step, and this by means of the intermediate gears 50 and 47 turns the cam wheel 45, and when a notch 46 is registered 60 with the point 47 the lever 41 is pulled in by the spring 44, engaging the gears 40 and 39 and permitting the seconds hand to be driven from the arbor 32 through the gears

43, 40, 39, and arbor 37, the lever 60 being at the same time lifted from the heart cam, 65 as shown in Fig. 1, in consequence of the drop of the point 61 into one of the notches 46, and the seconds hand continues to move until the glass is again pushed in, which turns the cam wheel 45 and swings the lever 70 41 to disengage the gears 40 and 39, and stop the seconds hand, and another push will then lift the point 61 from the notch 46 and throw the opposite end of the lever 60 against the heart cam, which returns the 75 seconds hand to original position. A spring 70 serves to lift the pin 54, after the pressure thereon is released.

In consequence of the construction shown and described, the in and out shift of the 80 casing 7, and the rotation thereof for setting the hands or winding the spring, as disclosed in my said applications, is not interfered with, the use of the additional bezel 57 to hold the glass permitting the 85 rim 8 to be pulled out or turned as desired.

Although described in connection with a clock having a shifting and rotatable casing, it will be obvious that the operating 90 devices for the stop movement may be applied to a clock having a fixed casing. That is, assuming that the casing 7 and rim 8 are fixed, the bezel 57 may be nevertheless pushed in to operate the push pin for the 95 purpose stated.

I claim:—

1. The combination with a clock or watch movement, and its casing, of a stop hand and means to drive the same by said movement, and means to manually control the operation of said stop hand, including a hinged bezel which may be pushed in to actuate said means.

2. The combination with a clock or watch 100 movement, and its casing, of a stop hand and means to drive the same by said movement, and means to manually control the operation of said stop hand, including a bezel movable in and out to actuate said 110 means.

3. The combination with a clock or watch movement and its casing, of a stop hand, and means to drive the same by said movement, of means to manually control the 115 operation of said stop hand, including a push pin located behind the bezel, and a bezel bearing upon said push pin and movable in and out, so that the push pin may be operated by pressure on said bezel.

In testimony whereof, I affix my signature in presence of two witnesses.

WALTER E. E. MILZ.
